UNITED STATES PATENT OFFICE.

FRANCIS RANKEN, OF KINGSWAY, LONDON, ENGLAND.

BOMB.

1,395,769.

Specification of Letters Patent.

Patented Nov. 1, 1921.

Application filed September 16, 1919. Serial No. 324,207.

(GRANTED UNDER THE PROVISIONS OF THE ACT OF MARCH 3, 1921, 41 STAT. L., 1313.)

To all whom it may concern:

Be it known that I, FRANCIS RANKEN, a subject of the King of Great Britain and Ireland, and residing at the Air Ministry, 5 Central House, Kingsway, London, W. C., 2, England, have invented certain new and useful Improvements in or Relating to Bombs, for which I have filed an application in Great Britain, Sept. 13, 1917, Patent 10 #134,559, and of which the following is a specification.

This invention relates to bombs of the incendiary type and has for its object to provide a bomb of small dimensions which is 15 simple to construct but effective in operation and is adapted to be used singly or in groups which are discharged from a container.

According to this invention a cylindrical 20 casing is provided which is closed and weighted at one end where a striker is positioned. A separate cartridge which contains an incendiary composition and a detonator cap at one end is adapted to be inserted in the casing so that on impact the 25 cartridge will slide within the casing when the cap will be detonated by the striker. As a result the cartridge is ejected from the casing and the incendiary composition 30 is ignited. The cylindrical casing has one end closed by a separate plug which constitutes the weight the striker being formed or mounted on one face of this plug. The 35 other end of the cylinder is closed by a detachable cap which can be sprung into place and is preferably provided with wings or vanes. The cartridge comprises a cylindrical metal container for the incendiary composition and a head which carries the detonator cap. The cartridge is a loose fit 40 within the casing into which it is inserted and the head then lies against tongues which are struck inward from the wall of the casing and keep the head of the cartridge clear 45 of the striker.

In the preferred construction the cartridge container tube is formed of aluminium and

the incendiary composition is of the thermit class and conveniently made up as follows:

Powdered aluminium	3 parts.	50
Barium nitrate	6 parts.	
Hammer-scale	8 parts.	

The approximate weight of this composition is $1\frac{1}{2}$ oz. and it is compressed into the 55 container so as to occupy half its natural volume. As the ignition temperature of this composition is fairly high a layer of igniting composition is preferably used and composed as follows:

Barium nitrate	$1\frac{1}{2}$ parts.	60
Powdered aluminium	5 parts.	
Sulfur	6 parts.	
Potassium nitrate	$1\frac{1}{2}$ parts.	
Shellac	$\frac{3}{4}$ parts.	65

This composition is moistened with methylated spirits and pressed into place. A priming is used which is composed of gun powder dust moistened with spirit varnish 70 and pressed into place, the spirit varnish being made up of 6 lbs. of shellac to one gallon of methylated spirits. The detonator cap as also the head of the cartridge is 75 preferably formed as in an ordinary sporting cartridge.

In use a bomb thus constructed is adapted to be released from an aircraft and when it strikes an object the cartridge within the casing will slide forward on to the striker 80 shearing or deforming the safety device in its passage along the container. A number of these bombs may be grouped in a suitable receptacle and arranged so that when released they will fall in successive bunches. 85

The accompanying drawings illustrate by way of example alternative constructions of the improved bomb. In these drawings

Figure 1 is a longitudinal sectional elevation of the bomb the cartridge being 90 shown in dotted lines.

Fig. 2 is a longitudinal sectional elevation of the cartridge.

Referring to Fig. 1 the bomb comprises an

outer cylindrical casing A one end of which is closed by a plug B constituting a weight. The plug is conveniently formed cylindrical of mild steel with an annular recess or cannelure B¹ toward one end into which the end of the cylinder A is rolled or with which the cylinder is otherwise caused to engage as by clenching at several points. About the center of the inner end face of the plug 10 is a projection B² which serves as a striker. A cap C on which are formed or mounted wings D is sprung on to and closes the opposite end of the casing A.

The cartridge as shown in Fig 2 has a 15 casing E formed as a tube of aluminium with one end closed as at E¹. On the other end of the tube E is fixed a cartridge head F of normal type provided with the usual detonator cap at its center and held in place 20 either by stabbing (i. e. indenting slightly the tube E at one or more points M) or in some other convenient manner. The cartridge case E is mainly filled with the incendiary composition G which as mentioned 25 is of the thermit class and made up conveniently as indicated above for example of barium nitrate, aluminium dust and hammer-scale pressed dry into the case E. On this composition is placed a layer H of igniting composition conveniently made up of barium nitrate, potassium nitrate, sulfur, aluminium dust and shellac all moistened 30 with methylated spirit and pressed into the casing on to the top of the incendiary composition. On the igniter H lies a priming 35 layer H¹ (say of gunpowder dust) above which is a layer of flattened quickmatch J with a card washer K next it.

Two tongues A¹ are struck inward from 40 the wall of the casing A so that these tongues will project into the interior of the casing a short distance from the inner face of the plug B. When the cartridge is within the casing as shown in dotted lines in Fig. 1 45 the head F of the cartridge rests on the tongues A¹ and is thus kept away from the striker B². On impact the cartridge head will shear or deform the tongues A¹ then the cartridge detonator will be brought down 50 upon the striker B².

Two oppositely disposed indentations A² are made in the wall of the casing A in approximately the position shown in Fig. 1. When the cartridge E is inserted into the 55 casing through the open end of the latter before the cap C is put into place the head of the cartridge is pressed past the indentations A² which will spring apart so that the head of the cartridge will reach and rest on the tongues A¹. The indentations A² then prevent the cartridge from passing out of the rear or open end of the casing A until 60 expelled by the detonation of the cap.

Having now described my invention, what I claim as new and desire to secure by Letters Patent is:—

1. An incendiary bomb including in combination a cylindrical casing, a heavy member in one end thereof, a separate cartridge with incendiary composition therein contained in said casing, a detonator cap detachably secured to said separate cartridge containing means adapted upon impact of the bomb to separate said cartridge from said cap and to expel the cartridge from said 75 casing.

2. An incendiary bomb including in combination a cylinder, a plug constituting a weight in one end of said cylinder, a striker in center of said plug, a detachable cap for 80 the other end of said cylinder, a separate cartridge, an incendiary composition therein, and a detonator cap for said cartridge adapted to be detonated by said striker upon impact, and tongues inwardly projecting 85 from the cylinder and supporting said cartridge.

3. An incendiary bomb including in combination a cylinder, a plug constituting a weight in one end of said cylinder, a striker 90 on said plug, a readily detachable cap for the other end of said cylinder, a separate cartridge with incendiary composition therein and a detonator cap attached to said cartridge and containing means adapted upon 95 impact between said detonator cap and said striker to expel said cartridge from said cylinder.

4. An incendiary bomb including in combination a cylinder, a plug constituting a 100 weight in one end of said cylinder, a striker in center of said plug, a detachable cap for the other end of said cylinder, vanes on said cap, a separate cartridge closed at one end, a head on the other end of said cartridge, 105 including a detonator cap, incendiary material and igniting means and a washer in said cartridge, tongues inwardly projecting from the cylinder, and supporting said cartridge, and internal projections in said cylinder retaining said cartridge in position: 110

5. An incendiary bomb including in combination a cylinder, a plug constituting a weight in one end of said cylinder, a striker in the center of said plug, a detachable cap 115 for the other end of said cylinder, a separate cartridge with incendiary composition therein and a detonator cap therefor adapted to be detonated by said striker upon impact and means in said cylinder adapted normally to support said cartridge with its detonator cap out of contact with said striker.

In testimony whereof I have signed my name to this specification.

FRANCIS RANKEN.
